UNITED STATES PATENT OFFICE.

LEO STRAEHL, OF DETROIT, MICHIGAN.

FIRE-ESCAPE.

SPECIFICATION forming part of Letters Patent No. 289,163, dated November 27, 1883.

Application filed October 1, 1883. (No model.)

To all whom it may concern:

Be it known that I, LEO STRAEHL, of Detroit, in the county of Wayne and State of Michigan, have invented new and useful Improvements in Fire-Escapes; and I hereby declare that the following is a full, clear, and exact description thereof, reference being had to the accompanying drawings, which form a part of this specification.

10 This invention relates to certain new and useful improvements in the construction of fire-escapes, by means of which a person may lower himself from the upper portion of a building with perfect ease and safety; and the 15 invention consists in the peculiar construction, arrangements, and combinations of the parts, all as more fully hereinafter set forth.

Figure 1 is a perspective view of my improved device as in use. Fig. 2 is an eleva- 20 tion.

In the accompanying drawings, which form a part of this specification, A represents a tube, which may be formed solid or in two parts and secured together by suitable screws, 25 and bent into the form of an S, as shown. This tube A is provided with studs a, and in these studs I properly journal the grooved friction-wheel B, which has slotted bearings in said studs, and to other studs, b, I pivotally secure one end of the lever C, the opposite or free end of which is perforated and slips over the screw-stud D, which latter receives upon its outer end the winged nut E. Upon the lower side of this tube A, I form a 35 loop, c, into which is rigidly secured one end of the strap F, the opposite end of which is provided with a snap-hook, designed to engage with the ring d upon the waist-belt G, which is buckled around the person using the 40 device.

H represents a rope, one end of which is

passed through the tube A, and carries upon that end a hook, I, which is likewise designed to be hooked into the ring d.

In practice the belt is buckled around the 45 waist of the person desiring to escape from the building, with the ring d in front, and the strap F and rope hooked into this ring. The loop formed by the rope between the ring d and the tube A is then passed through 50 the proper hook, J, which should be rigidly or firmly screwed into the floor or other convenient part of the room. The person now lets himself out of the window, and governs the rapidity of his descent by grasping the tube in his hand, as shown in the drawings, and compressing the grooved friction-roller upon the rope by means of the lever, and it can readily be seen that the operator can easily stop himself at any desired point. 60

This device is simple in its construction, and can readily be rolled up into a small compass and carried in a valise. It will be seen that, independent of the friction device proper, there is a large amount of friction, due to the 65 rope passing twice over the window-sill and around the hook J.

I am aware that S-shaped tubes with friction devices are not new in fire-escapes, and therefore do not claim, broadly, such constructions. 70

What I claim as my invention is—

In combination with the belt G, strap F, and rope H, the S-shaped tube A, provided with the grooved friction-wheel B, regulating- 75 lever C, screw - stud D, and nut E, substantially as and for the purposes specified.

LEO STRAEHL.
